UNITED STATES PATENT OFFICE.

SAMUEL MACFERRAN, OF PHILADELPHIA, PENNSYLVANIA.

IMPROVEMENT IN MODES OF SECURING IRON RAILINGS TO THEIR POSTS.

Specification forming part of Letters Patent No. **38,049**, dated March 31, 1863.

To all whom it may concern:

Be it known that I, SAMUEL MACFERRAN, of the city and county of Philadelphia, and State of Pennsylvania, have invented a new and useful Improvement in Securing the Panels of Iron Railings to their respective Posts; and I do hereby declare that the following is a full, clear, and exact description of the same, reference being had to the annexed drawings, making a part of this specification, in which—

Figure 1 represents a panel of railing attached to its respective posts by the improved method. Fig. 2 is a longitudinal section on an enlarged scale of the combined pin and nut, and a portion of the rod B, to which it is attached. Fig. 3 is a transverse section of the same.

Like letters in all the figures refer to the same parts.

The nature of my invention consists in a combined pin and nut for securing panels of iron railings to their respective posts, constructed and arranged in the manner I will hereinafter describe.

To enable others skilled in the art to make and use my invention, I will proceed to describe its construction and operation.

In the ordinary method of securing the panels of railings to their respective posts, when the different sections of the panels are held together by longitudinal rods, the ends of the rods enter corresponding holes in the sides of the posts, and are secured by means of nuts in the hollow or perpendicular opening of the posts. This makes it necessary to cast the posts in several pieces, which are secured together by vertical rods to enable them to be taken apart to insert a wrench in the inside of the posts to screw and unscrew the nuts on the ends of the rods, and consequently increased expense is incurred and trouble experienced in adapting the posts to this system of fastening and detaching and securing their parts together. Now, instead of passing the ends of the wrought-iron rods B through the sides of the posts A and securing them thereto by means of nuts inside of the posts, as heretofore, I form on the ends of said rods B screw-threads, on which the nuts are screwed, for the purpose of securing the panels to

the posts, and, in lieu of the nuts heretofore employed for the purpose, I provide nuts C, which may be made of either round, octagonal, or other form, and combine with the said nuts coupling-pins D, which are at right angle to the screw-holes of the nuts, and which project about an inch and a half, more or less, from the peripheries of the nuts. In addition to this special design the pins act as purchases for screwing and unscrewing the nuts, and in thus dispensing with the use of the wrench the progress of the work is much facilitated. The combined thickness of the several rings, E, for confining the sections of the panel on the horizontal rods B is such as to bring the coupling-pins D in vertical position, when the nuts C are screwed tight to enable them to drop readily into corresponding vertical openings in projections or lugs F on the sides of the posts A, and in this manner to secure the panel in its proper position between the posts, when the latter are firmly planted on their bases. The combined pin and nut C D, I usually make of malleable iron; but, if desired, they may be made of wrought-iron, the pin being screwed or otherwise fastened in the side of the nut.

From the foregoing it will be observed that the panels of the railings can be attached and detached from their respective posts A by the simple act of lowering and raising the same, so as to drop the coupling-pins D on the nuts C into and lift them from the openings in the lugs F, and that the trouble and expense before referred to in the old system are in this case entirely avoided. In case it is desired, the coupling-pins D on the nuts C of either the lower or upper rod, B, may have threads and nuts on them to more firmly secure the panels to the posts.

It will readily be seen that my combined pin and nut is not only adapted to securing panels to the posts, when the former are made in sections and attached to horizontal rods, but also when the panels are in single pieces, which, should they not have rods extending their whole length, may have pins projecting from their ends to receive the nuts. The plan of combining the combined pin and nut to the panel may be indefinitely modified to suit any peculiar construction of the latter.

I hang gates to their posts by means of the

combined pin and nut, arranged on the edge of the gate in the same manner as on the stationary panel above described.

What I claim as my invention, and desire to secure by Letters Patent, is—

The combined pin and nut, constructed, arranged, and operating substantially in the manner and for the purposes set forth.

In testimony that the above is my invention I have hereunto set my hand and affixed my seal this 15th day of April, 1862.

SAMUEL MACFERRAN. [L. S.]
